BORIS ANISSIMOFF, OF MANILA, PHILIPPINE ISLANDS.

DEVICE FOR REDUCING THE SKIN AND WAVE RESISTANCE OF MOVING BOATS.

Application filed January 10, 1928. Serial No. 245,746.

My invention relates to boats and an object thereof is to provide a boat wherein skin resistance to the water in which the boat is moving is reduced to a minimum and thus permit the boat to attain a greater speed.

Further the invention provides a compressed fluid apparatus for discharging fluid currents over the boat's surface to counteract resistance to the latter by the body of water in which the boat is travelling.

With the preceding and other objects and advantages in mind, the invention consists in the novel combination of elements, constructions and arrangement of parts to be hereinafter specifically referred to, claimed and illustrated in the accompanying drawings, wherein:

Figure 1 is a side elevation of a boat embodying my invention, parts of the latter being illustrated in broken lines;

Figure 2 is a bottom plan view of the same;

Figure 3 is a fragmentary horizontal section on line 3—3 of Figure 1;

Figure 4 is a similar view taken on line 4—4 of Figure 2;

Figure 5 is a fragmentary perspective of one of the fluid conducting conduits or jets attached to the boat hull; and

Figure 6 is a perspective of the valve element arranged in each of the fluid conducting conduits or jets.

Referring to the invention in detail a conventional boat or water craft 5 is provided, and mounted therein is an air compressor 6 adapted to discharge compressed air over the boat's surface to counteract the resistance to the latter by the body of water in which the boat is travelling.

To conduct the compressed air from the compressor and discharge it over the bow of the boat, a main conduit 10 extends longitudinally of the boat's bottom centrally thereof and upwardly around its prow, and communicating therewith is a plurality of rearwardly inclined parallel branches 15 which are disposed upon the outer face of the hull. The conduit 10 extends from a point slightly below the normal low water line of the boat to the end of the bow, while the branch conduits terminate at points below the normal low water line.

As illustrated in Figure 4, the forward end of the conduit is V-shaped in cross-

section, as indicated at 20, to conform to the cross-sectional contour of the prow, and is formed with rearwardly extended marginal flanges which are secured to the prow by rivets or other suitable fastenings 22.

The conduits 15 comprise longitudinally curved plates 23 which conform to the contour of the hull, and longitudinally curved channel shaped members 24 having marginal flanges 25 which are riveted or otherwise secured to the plates, as at 26. Transverse fastenings 27 pass through the flanges, plates and hull to secure the branch conduits in place.

It is proposed to discharge air jets over the boat hull at points of greatest resistance to the water, and to that end the V-shaped part of the conduit 10 is provided with rows of perforations 28 upon opposite sides of the prow rearwardly of its apex. Similar openings 29 are provided in the rear wall of each of the branch conduits in close proximity to the hull.

An air supply pipe 30 leads from the air compressor and communicates with the main conduit, intermediate its ends, to be conducted through the latter and branch conduits to play upon the outer surface of the hull, in the form of jets.

To permit a predetermined air pressure to pass through each of the branch conduits, according to the water pressure or water resistance, a plate valve 31 is pivotally arranged in each of the branch conduits adjacent its inner end, the latter having an upstanding pin 32 which is pivotally engaged with the outer wall of its respective branch conduit and formed with a head 43 whereby the valve may be adjusted about its axis. As illustrated in Figure 6, the valve is the same configuration as the cross-sectional contour of the branch conduits, and when in fully closed position extends transversely of the branch conduits.

For the purpose of controlling the operation of the compressor a vertically extending pipe 34 leads from the compressor to the bridge of the boat and is provided with a control valve 35.

With my invention it will be observed that fluid pressure is discharged in jets over the outer surface of the boat's bow against the water, impelling the latter away from the boat and thus reduce the friction or skin of the water to the boat.

What is claimed is:

1. In combination a water craft, a main conduit extending longitudinally and exteriorly thereof, a plurality of parallel perforated branches communicating therewith, and means for supplying fluid pressure to the conduit to be discharged in jets over the craft's surface to overcome the resistance of a body of water in which the craft is travelling.
2. In combination a water craft, a main conduit extending longitudinally and exteriorly thereof, a plurality of parallel perforated branches communicating therewith, means for supplying fluid pressure to the conduit to be discharged in jets over the craft's surface to overcome the resistance of a body of water in which the craft is travelling, and a valve in each branch conduit for controlling the passage of fluid pressure therethrough.
3. In combination a water craft, a main conduit extending centrally along its bottom and having its forward end extended

around the craft's prow, said forward end having perforations, a plurality of branch conduits communicating with the first mentioned conduit and extending upwardly along the craft's hull and also provided with perforations, and an air compressor communicating with the first mentioned conduit.

4. In combination a water craft, a conduit extending longitudinally of its bottom and having a forward V-shaped in cross-section extremity embracing and attached to the prow of the craft and provided with perforations, a plurality of parallel branch conduits communicating with the first mentioned conduit and having perforations in the rear walls thereof, and means for supplying compressed fluid to the first mentioned conduit to be discharged through the perforations onto the outer surface of the hull to react upon the water in close proximity to the craft and force the water away from the same.

BORIS ANISSIMOFF.
